ROBERT S. WALLACE, OF POCAHONTAS, VIRGINIA

RAIL BOND

Application filed February 11, 1927. Serial No. 167,463.

This invention relates to certain improvements in rail bonds; and the nature and objects of the invention will be readily recognized and understood by those skilled in the art from the following description and detailed explanation of the accompanying drawings illustrating what I at present consider to be the preferred embodiments or mechanical expressions of my invention from among various other forms, arrangements, combinations and constructions of which the invention is capable within the spirit and the scope thereof.

In particular, although not so limited, the invention is directed to the solution of certain problems and the elimination of certain difficulties encountered in bonding or electrically connecting the rails, at the splices or joints therebetween, of railway track of the types for use with mine cars or similar rolling stock. The general form of rail joint or splice employed with mine car track embodies the use of opposite fish-plates or splice bars bolted to and through the rails by transverse bolts, and the usual manner of bonding the rails of such track to electrically connect the same, is to secure a suitable length of conducting material, such as stranded copper cable, at its opposite ends to the outer sides of the spliced rails at opposite ends of the splice, with the conductor so secured extending across and spaced outwardly from the rails and splice to bridge the splice and electrically bond the rails, as will be understood by those familiar with these types of track.

In the operation and use of mine car track formed of rails electrically connected or bonded at the splices or joints in accordance with the general type of bond referred to above, a serious problem in upkeep and maintenance, as well as in operation of the rail circuits, is encountered due to the frequent breakage, cutting, mutilation or other injury to the rail bonds by the derailment of cars and resulting engagement of the rail bonds by the car wheels or flanges thereof, which engagement is facilitated by the length of the bonds and the outward spacing thereof from the rails at the splices. A further difficulty and disadvantage is met with in the use of such types of

bonding because of the necessity for severing or breaking the bonds from the rails to disconnect the same when a rail is or rails are removed from the track for replacement, or where the track or a portion thereof may be dismantled for any desired purpose, so that the bonds so severed or disconnected are rendered practically incapable of reuse in bonding other rails or rebonding the removed or replaced rails.

One of the fundamental objects of the invention is to overcome the foregoing difficulties and disadvantages encountered with rail bonds, by the provision of a design and construction of rail bond which reduces and practically eliminates possibility of breakage or injury thereto from derailed rolling stock, as well as injury through contact from other sources, and which bond is readily removable from rail bonding position without deformation or injury, and when removed is capable of immediate reuse and application to a rail joint or splice to electrically bond and connect the rails.

Another object of the invention is to provide a bond for electrically connecting spliced rails which bond is so designed as to form a part or element of the rail splice and thereby reduce the parts or elements required for the splice with resulting simplicity in structure and reduction in cost of the spliced and bonded rails.

Another object of the invention is to provide a rail bond for electrically connecting spliced rails, which is of simple, durable construction capable of efficiently maintaining the rails electrically connected under all conditions of service, and which is further designed for ready application to and removal from the rails and for reuse after removal.

With the foregoing general objects, and certain other aims and objects in view, which will be readily recognized and apparent to those skilled in the art from the following explanation, the invention consists in certain novel features in construction and in combinations and arrangements of elements, as will be more fully and particularly referred to and specified hereinafter.

Referring to the accompanying drawings,

in which similar reference characters refer to corresponding elements throughout the several figures thereof:

Fig. 1, is a view in side elevation of a rail bond and splice of the invention applied to and connecting the ends of a pair of rails.

Fig. 2, is a view in top plan of Fig. 1.

Fig. 3, is a horizontal section taken on the line 3—3 of Fig. 1.

Fig. 4, is a transverse vertical section taken on the line 4—4 of Fig. 1.

In the accompanying drawings, the ends of a pair of rails R are disclosed in alined, track forming position for splicing or joining, in the usual or any other desired manner familiar in the art, and in the example hereof the rails R are joined or spliced in track forming position by means of the fish-plates or splice bars S disposed against opposite sides of the rails, across the joint between the rail ends, and between the head and base flange of the rails. Suitable headed bolts B are extended transversely through the splice bars S, adjacent the opposite ends thereof respectively, and the rails R, and are secured in position to clamp the splice bars S against opposite sides of the rails to bind the latter in joined, spliced relation, by the nuts B', as will be readily understood by those familiar with rail splices upon reference to the drawings hereof.

The rails R so joined and spliced are required to be electrically connected to form track circuits for carrying electric currents, and this is generally accomplished by connecting the rails with an electrical conductor or bond. According to the present invention, a bond is provided for electrically connecting the spliced rails R, which embodies, referring now to Figs. 2 and 3 of the drawings in particular, a bar or rod 10 of suitable conducting material, preferably copper, which is bent or otherwise brought into U-shape form to provide the opposite spaced and substantially parallel legs or bolt forming members 11, connected by the base or bridge member 12. The bolt members 11 are externally screw threaded and the nuts 14 are threaded inwardly thereover onto the inner ends thereof at and adjacent the base or bridge member 12. The bridge member 12 of the bond 10, is bent or depressed inwardly at the central portion thereof between bolt members 11 a distance substantially equal to the thickness of the nuts 14, in the present example, although the invention is not limited to the extent of the depressed central portion of bridge 12. This depressed or reentrant central portion of bridge 12 is an important feature of the present invention and will be more fully referred to hereinafter.

Each bolt forming leg or member 11 of the bond bar 10, is provided with a nut 15 threaded onto the outer end thereof, and a

pair of conductor plates 16, preferably formed of copper sheet, although not so limited, are mounted loosely over and onto the bolt members 11, extending therebetween and thereacross. Suitable holes or bores are provided through plates 16 adjacent their opposite ends to loosely receive bolt members 11, as will be clear by reference to Figs. 1 and 3 of the drawings. In the example hereof, the conductor plates 16 are formed of a width substantially equal to the width of the splice bars S, with the bolt holes therethrough disposed approximately along the longitudinal center line of the plates. Thus, a bonding unit is provided for application to and as a securing element of a rail splice or joint, in a manner hereinafter described.

With the usual rail splice or joint embodying the splice bars S and the outer end transverse bolts B, another set of bolts, similar to bolts B, are employed adjacent the inner ends of the alined rails R, and traversing the splice bars S and the rails, but with and according to this invention, these bolts are dispensed with and rendered unnecessary, the splice bars and rail webs however, are provided with the usual alined bolt receiving bores for such bolts, as clearly disclosed in Fig. 3 of the drawings. The bond unit of the present invention, constructed as above described, is applied to the splice formed at the rail ends by splice bars S and bolts B, by removing the outer nuts 15 and outer conductor plate 16 from the bolt members 11, and these bolt members 11 are then inserted in and through the inner bores of the splice bars S and rail ends, to a position with the inner conductor plate 16 against the adjacent splice bar S at the outer sides of rails R, and the nuts 14 in position bearing against, and forcing said conductor plate against the splice bar. The opposite conductor plate 16 is placed over the projecting ends of the bolt members 11, and the nuts 15 are screwed onto the bolt ends to position forcing the conductor plate 16 against the adjacent splice bar and drawing the bond into applied position with the nuts 14 and 15 thereof clamping the conductor plates 16 and splice bars S therebetween to complete the splice of the rails R and electrically connect the same.

In the foregoing applied position of the bond of the invention an efficient electrical connection is established and maintained between the spliced rails R, through the U-shaped conductor bar 10 of the bond, nuts 14 and 15, and the conductor plates 16 in electrical contact with the rails R through the splice bars S. Due to the construction and arrangement of the bridge 12 between the legs or splice bolt forming members 11, whereby the central portion of bridge 12 is depressed or bent inwardly toward the rails, in the present example engaging the adjacent conductor plate 16, a minimum projec-

tion of the bond beyond the outer side of the rails is secured, so that the possibility of injury to the bond by the wheels of derailed rolling stock, or from engagement with other elements, is practically eliminated. This result is further contributed to by the small length of the bridge due to the minimum spacing of bolt members 11. The entire bond at both sides of the splice, and particularly at the outer side, is disposed in close proximity thereto with a minimum projection to catch or engage car wheels or other objects capable of injuring the same.

The bond further provides an element of the rail splice to secure the rails clamped in track forming position through the medium of bolt members 11 and the clamping nuts 14 and 15 thereof, and thus reduces the necessary elements for the splice and bond for the rails with a reduction in cost. The bond unit is readily detachable and removable from the rail splice without injury to the bond, so that it is capable of repeated reuse. The removal and replacement of rails bonded by the invention is readily accomplished and the original bonds can be employed, or track can be dismantled and relaid without the use of new bonding, the original bonds simply being again used.

If desired or found expedient, in place of nuts 14, the inner ends of the bolt members 11 can be formed with integral enlarged portions as equivalents and to take the place of the applied nuts 14, disclosed and described in the example hereof.

While the invention is particularly directed to use in track for mine cars and such classes of rolling stock, it is not so limited, but is of general application to the bonding and splicing of railway track or other rails, and the invention intends and contemplates such broad uses and applications.

It is also evident that various changes, modifications, variations and substitutions might be resorted to without departing from the spirit and scope of my invention, and hence I do not wish to limit myself to the exact and specific disclosures hereof.

Desiring to protect my invention in the broadest manner legally possible, what I claim is:

A rail bond and splice embodying in combination with joined rails, splice bars at opposite sides of and across the joined rail ends, and a readily removable rail bonding and splice securing member comprising a bar of electrical conducting material formed into approximately U-shape to provide spaced bolt members connected at one end by a bridge forming base, said bolt members extended transversely through the splice bars and rails at opposite sides of the rail joint with the base bridging the rail joint, clamping members on said bolt members at the inner ends thereof adjacent said connecting base, an

electrical conductor plate mounted over and across said bolt members between said clamping members and the adjacent splice bar, an electrical conductor plate mounted over and across the outer extended ends of said bolt members, nuts on the outer ends of said bolt members with the splice bars, rail ends and conductor plates clamped between said nuts and clamping members, and the said bridge forming base extended inwardly between said clamping members to provide the intermediate portion thereof positioned within and between said clamping members and in electrical contact with the adjacent conductor plate, the said rail bonding and splice securing member with the conductor plates being removable from the rail splice without injury for reuse.

Signed at Pocahontas, Virginia, this 6th day of May, 1926.

ROBERT S. WALLACE.
